UNITED STATES PATENT OFFICE.

ALFRED COPONY, OF CHICAGO, ILLINOIS, ASSIGNOR OF ONE-HALF TO CHARLES R. COOPER, OF CHICAGO, ILLINOIS.

CAR-DOOR.

1,221,971.

Specification of Letters Patent. Patented Apr. 10, 1917.

Application filed September 10, 1915. Serial No. 49,982.

To all whom it may concern:

Be it known that I, ALFRED COPONY, a subject of the Emperor of Austria, residing at Chicago, in the county of Cook and State 5 of Illinois, have invented new and useful Improvements in Car-Doors, of which the following is a full, clear, concise, and exact description, reference being had to the accompanying drawing, forming a part of this 10 specification.

My invention relates to car door construction and more specifically to a construction for use in refrigerator cars.

Among the objects of my invention is to 15 provide a circular door which eliminates the eight corner joints of the construction now in use, and an improved construction which will be air tight and which will not easily get out of order.

20 In the drawings in which I have shown one embodiment of my invention—

Figure 1 is a side elevation of part of the car showing the door in closed position;

25 Fig. 2 is a side elevation similar to Fig. 1, but showing the door open;

Fig. 3 is a vertical section substantially on the line 3—3 of Fig. 1 showing the door in full lines within the door frame, and in dotted lines withdrawn from the 30 door frame;

Fig. 4 is a section on the line 4—4 of Fig. 1; and

Fig. 5 is a section on the line 5—5 of Fig. 1.

35 Referring now to the drawings in detail, the portion of the car shown comprises the sill 10, the floor 11 above the sill, the lower side frame member 12 secured to the sill 10, the upper side frame member 13, the 40 ceiling 14 supported from the side frame 13 and the siding 15 extending between and secured to the side frames 12 and 13.

The siding 15 is cut away to provide a 45 circular doorway 16 adjacent which is secured the circular door frame 17. This door frame 17 comprises an arcuate member 17^a the ends of which are secured to the floor 11 of the car and intermediate points of which are secured to diagonal 50 braces or supports 17^b, which, in turn, are secured to the uprights 17^c and to the frame members 12 and 13. The arcuate member 17^a is provided with an annular groove 18 for coöoperating with an arcuate sealing 55 member carried by the circular door 19.

The door 19 is mounted on a swinging support 20 having at its lower end an off-set bracket or arm 21 pivotally mounted in a carriage 22 movable along a track 23 secured adjacent the side frame 12. 60

The upper end of the swinging support 20 is provided with an off-set guide roller 25 operating within a guide channel 26, mounted adjacent the upper side frame 13.

For effecting an air tight joint between 65 the door 19 and the door frame 17, a mechanism, indicated in general at 27, is provided, which mechanism comprises an annular sealing strip 28 located in a groove 29 in the periphery of the door 19, a plurality of bars 30, each rigidly secured to the strip 28 and located and guided in radial passages 31 adjacent to the periphery of the door, a plurality of links 32, one pivotally 70 connected to each of the bars 30, a rotatable 75 disk 33 to which all of the links 32 are pivotally connected, a shaft 34 to which the disk 33 is secured, a bearing plate 35 secured to the door 19 in which the shaft 34 is rotatably mounted and an operating 80 lever 36 secured to the shaft 34 for rotating the latter.

A cork or rubber lining 37 may be provided for the sealing strip 28 and a canvas strip 38 may be loosely secured across the 85 groove 29 to assist in holding the strip 28 in its proper position and to insure an air tight joint at all points between the door and the door frame.

For holding the lever 36 in proper position to effect an air tight joint between the door and the door frame, a quadrant 39 is provided which is secured to the door 19 and the lever 36 is provided with a pin 40 which is slidably and rotatably mounted 95 in the lugs 41 on the lever to be moved into and out of openings in the quadrant 39.

The pin 40 is provided with an arm 42 which, when the pin enters one of the openings in the quadrant 39, can be swung over 100 to a position above the lug 45 on the lever 36.

The arm 42 and lug 45 are provided with registerable openings through which a seal or other suitable securing means may be 105 inserted to prevent the pin 40 from disengaging the openings in the quadrant 39.

The swinging support 20 comprises a semi-circular portion 47 forming in effect an operating lever and a loop or handle por- 110

tion 48 affording a convenient means for operating the swinging support.

As shown in Fig. 1, when the door is in position within the frame and the lever 36 is moved over to the dotted line position shown, to effect a tight joint between door and frame, the upper end of the lever will be in a position to prevent outward movement of the semi-circular portion 47 so that the 10 operation of effecting a tight joint between the door and frame will also lock the swinging member 20 and prevent the door from being moved outwardly.

The door 19 comprises a plurality of segmental frame members 49 having cut away over-lapping portions 50 (Fig. 4) which are secured to each other in any suitable manner, as by means of screws 51, inner and outer sidings or casings 52 and 53 respectively secured to the frame members 49, inner and outer cork layers 54 and 55 respectively located adjacent sidings 52 and 53 and partitions 56 and 57 spaced from each other and from the cork layers 54 and 55 25 whereby dead-air spaces 58, 59 and 60 are provided as shown in Fig. 4.

Two semi-circular flange members 61 and 62 are secured to the outer face of the door to limit the distance to which the door enters the frame and also to aid in effecting a tight joint.

Any suitable fastening means such as screws 63 are provided for securing the flange members 61 and 62 on the door.

The track 23 is provided with upturned ends 64 to limit the movement of the carriage 22 and is supported in position on the frame by means of brackets or hangers 65.

The guide channel 26 is supported in position on the side frame 13 by means of hangers 66.

The operation of my improved device is as follows: Assuming that the car door is in the open position shown in Fig. 2 and it is desired to close the door, it is moved over to the left until the carriage is stopped against the left hand upturned end 64 on the track 23, in which position the door will be opposite the opening 16 in the side of the car. The handle 48 of the swinging member is then grasped and the member 20 swung from the position shown in Fig. 2 to the position shown in Fig. 1. This will cause the door to be moved from the position shown in dotted lines in Fig. 3 to the position shown in full lines in Fig. 3. The inward movement of the door 19 will be limited by the engagement of the flange members 62 with the side of the car. The lever 36 is then moved from the full line position shown in Fig. 1 to the dotted line position to cause the sealing strip 28 to be moved radially outward to enter the groove 18 in the door frame.

As previously stated, this movement of

the lever 36 also locks the swinging member 20 in position to prevent the door from moving out of the frame.

After the lever 36 has been swung to the left far enough to effect a tight joint between the door and the frame, the pin 40 is moved upwardly to engage one of the openings in the quadrant 39 and is then rotated to bring the arm 42 above the lug 45 on the lever 36 and to bring the openings in the arm 42 and the lug 45 into alignment to permit a seal to be inserted through these openings.

In opening the door the operations just described are reversed.

By making the door and door frame circular, the difficulties and disadvantages of the ordinary door with its corners which make it difficult to effect a tight joint, are avoided.

The lower part of the doorway 16 extends below the floor 11 as shown in Fig. 2 to facilitate the passage of a truck or the like in loading and unloading the car.

Having thus described my invention what I claim as new and desire to secure by Letters Patent is:—

1. The combination with a car having a circular door frame, of a circular door therefor, said door being provided with movable arcuate sealing means adjacent its periphery, and means for moving said sealing means toward said frame, said sealing means comprising two adjacent arcuate sealing portions moved in substantially opposite directions with respect to each other by the movement of said sealing means toward the frame.

2. The combination with a car having a circular door frame, of a circular door therefor, said door being provided with movable arcuate sealing means adjacent its periphery, and means for moving said sealing means toward said frame comprising a member rotatably mounted on said door and links connecting said rotatable member and said sealing means, said sealing means comprising two adjacent arcuate sealing portions moved in substantially opposite directions with respect to each other by the movement of said sealing means toward the frame.

3. The combination with a car having a circular door frame, of a circular door therefor, said door being provided with movable arcuate sealing means adjacent its periphery, and means for moving said sealing means toward said frame comprising a member rotatably mounted on said door and links connecting said rotatable member and said sealing means, and a lever for actuating said rotatable member, said sealing means comprising two adjacent arcuate sealing portions moved in substantially opposite directions with respect to each other by the

movement of said sealing means toward the frame.

4. The combination with a car having a floor and a circular door-frame, the lower 5 portion of the opening of which extends below the floor, of a circular door for said door-frame provided with a movable arcuate sealing member adjacent its periphery, and means for moving said member toward 10 said frame.

5. The combination with a car having a door frame, of a door therefor, said door being provided with a movable sealing member adjacent its periphery, and means for 15 moving said member toward said frame comprising a lever mounted on said door, a track, a carriage movable on said track, a swinging member mounted on said carriage on which said door is mounted to 20 move into and out of said frame, said swinging member and lever being so constructed and located that when the lever is operated to hold the sealing member in sealing position it will also hold the swinging member 25 in position to hold the door in the frame.

6. The combination with a car having a door frame, of a door therefor, said door being provided with a movable sealing member adjacent its periphery, and means for

moving said member toward said frame, 30 a track, a carriage movable along said track, a swinging member mounted on said carriage on which said door is mounted to move into and out of said frame, said swinging member and said means for moving said 35 sealing member being so constructed and located that when the latter is in position to hold the sealing member in sealing position it will also hold the swinging member in position to hold the door in the frame. 40

7. The combination with a car having a door frame, of a door therefor, said door being provided with a movable sealing member adjacent its periphery, and means for moving said member toward said frame, 45 a swinging member on which said door is mounted to move into and out of said frame, said swinging member and said means for moving said sealing member being so constructed and located that when the latter 50 is in position to hold the sealing member in sealing position it will also hold the swinging member in position to hold the door in the frame.

In witness whereof, I have hereunto sub- 55 scribed my name.

ALFRED COPONY.
